UNITED STATES PATENT OFFICE.

CHARLES P. MADSEN, OF CHICAGO, ILLINOIS, ASSIGNEE TO THE MICHIGAN STOVE COMPANY, A CORPORATION OF MICHIGAN.

ELECTRIC FLAT-IRON.

1,093,791.

Specification of Letters Patent.

Patented Apr. 21, 1914.

Application filed September 26, 1912. Serial No. 722,417.

To all whom it may concern:

Be it known that I, CHARLES P. MADSEN, a citizen of the United States of America, and a resident of Chicago, county of Cook, and State of Illinois, have invented certain new and useful Improvements in Electric Flat-Irons, of which the following is a specification.

The main objects of this invention are to provide an improved and more convenient method of controlling the current in electric flat irons; to provide an improved form of switch which is adapted to be operated to make a quick "make" and "break" in the circuit; to provide an improved construction of the flat iron handle for accommodating said switch; to provide an improved arrangement of the switch within said handle whereby it may be conveniently and quickly shifted; to provide improved means for connecting the electric conductors with the heating element of the flat iron; and to provide improved means of this kind particularly adapted for use in conjunction with the improved winding disclosed and claimed in my copending application executed by me of even date herewith and bearing Serial No. 722,416.

An illustrative embodiment of this invention is shown in the accompanying drawings in which—

Figure 1 is a side elevation partly in section. Fig. 2 is an enlarged sectional detail of the controlling switch and its casing, the section being taken on the line A—A of Fig. 1. Fig. 3 is an enlarged sectional detail taken on the line C—C of Fig. 1. Fig. 4 is an enlarged sectional detail taken on the line B—B of Fig. 2. Fig. 5 is an enlarged detail of the switch key. Fig. 6 is a detail, partly sectional, of a part of the rear handle support showing the construction whereby the electric conductors are connected to the wires leading to the heating element.

In the construction shown in the drawings, the flat iron comprises the heating plate 1 having a layer or coating 3 of insulating compound, on its upper side. The heating element 4 rests on the layer of insulating material and is forced against the same by a pressure plate 5. A screw 6 is connected to a central boss 7 in the plate 1 and has a nut 8 which bears against the

pressure plate 5 for holding the heating element against the insulating compound on the heating plate 1. These parts are housed within the body or casing 9 which in turn is secured in place by means of the ornamental nut 11 on the upper end of the central screw 6.

The handle 12 is of any suitable construction and is carried by tubular supports 13 and 14 located respectively at the front and rear ends of the casing 9, and extending through apertures 15 and 16 in the shell of the casing. The supports are suitably shouldered to engage the upper face of the casing 9, and their lower ends are threaded and provided with nuts 17 and 18 bearing against the inner face of the casing 9, and thus locking the supports rigidly in place.

A bolt 19 extends through the handle 12 from end to end and is secured by a nut 20 which serves to rigidly secure the handle between the upper ends of the supports 13 and 14.

The upper part of the forward tubular support 13 is enlarged to form a cap or housing 21 for the controlling switch 23, having a transversely shiftable switch member or push key 24 projecting through apertures at both sides of the casing 21. The member 24 has a central contact shifting-bar 25 which is constructed to engage and oppositely shift the contact member 26 into and out of engagement with the fixed contacts 27 and 28. A spring 42 on the stud 43 causes the switch to remain set in either open or closed position until the push key 24 is again operated to reverse the switch. It will be seen that mounting the switch in this manner renders it quickly and conveniently operated by the hand of the operator which grasps the handle, it being possible to shift the member 24 in respectively opposite directions by pressure of the operator's thumb and forefinger, thereby throwing the switch on and off without necessitating the release of the hand from the handle.

In order to protect the switch against injury, through the striking of the projecting ends of the key 24 against an obstruction in case the flat iron is accidentally overturned or falls, the adjacent metal part of the switch casing is provided with projecting lugs 24^a as shown in Fig. 3.

The rear tubular support 14 has a pro-

jecting casing on the plate or cap 29 which supports the handle 12. This casing comprises an integral part 30 and a removable cap 31 secured to the cap 29 by screws, and is provided for the purpose of housing the connections of the electric conductors to the wires connected to the terminals of the heating element.

The heating element 4 is provided with binding posts 33 and 34 located at the opposite ends thereof, which are connected by the wires 35 and 36 to binding posts 37 and 38 on the cap 29. The wire 36 leads up through the forward support 13 and is connected to the contacts 27 and 28 of the controlling switch. The electric conductors 39 lead into the neck 40 formed by the part 30 and cap 31 and are connected to the binding posts 37 and 38. The usual 20 spring 41 embraces the conductors 39, being secured in position thereon by the clamping of the end within the neck 40. This construction provides a convenient method for making connections of conductors to the heating element which may be conveniently 25 adjusted without necessitating the dismantling of the iron.

The operation of the device shown is similar to that of the usual electrically heated flat irons, with the exception of the ease and convenience with which the switch may be operated in the present invention. Other features of structural advantage will readily appear to those skilled in the art from an inspection of the drawings and the foregoing description.

Although but one specific embodiment of this invention has been herein shown and described, it will be understood that numerous details of the construction shown may be altered or omitted without departing from the spirit of this invention as defined by the following claims. Some of the features of novelty herein briefly described and illustrated in the drawings are not claimed herein but are made the subject matter of the copending application hereinbefore mentioned.

I claim:

50. 1. In an electric flat iron, the combination of a body portion, a handle mounted thereon, and a controlling switch located within said handle and comprising a movable operating member formed and arranged to project outwardly through the walls of the handle at opposite sides thereof to permit said operating member to be shifted in opposite directions by the thumb and forefinger respectively of the same hand which 60 grips the handle.

2. An electric flat iron comprising a body portion, a heating element in said body portion, a switch adapted to be set either open or closed and located in said handle, and a 65 tubular support connecting said handle and

body portion and serving as a conduit for conductors between said switch and heating element.

3. In an electric flat iron, the combination of a body portion, a heating element in said body portion, a handle having a casing at one end thereof, a controlling push switch mounted in said casing, a key projecting on each side for controlling the operation of said switch; and projecting ears on said casing for protecting said projecting key.

4. In an electric flat iron, the combination of a body portion; a pair of supports extending upwardly therefrom and having caps at their upper ends; a handle extending 80 between said supports and having its ends connected to said caps, one of said caps being hollow with an opening on each side; and a push switch mounted therein and operable through said opening.

5. In an electric flat iron, the combination of a bottom plate, a pressure plate, a heating element interposed between said plates, a hollow casing surrounding said pressure plate and heating element and coacting with 90 said bottom plate to form a housing therefor, tubular supports extending upward from said casing, a handle mounted between the upper ends of said supports, a switch at one end of said handle, and conductors 95 housed within said casing and supports and adapted to connect said heating element and switch in circuit with an outside source of electricity.

6. In an electric flat iron, the combination of a body portion, a heating element secured therein, a handle having a tubular support therefor mounted on said body portion, a pair of binding posts secured to said support, wires connected to said binding posts 1 and leading down through said tubular support and connected to said heating element, conductors connected to said binding posts, and a cap adapted to be secured over said binding posts and connections.

7. In an electric flat iron, the combination of a body portion, a heating element secured therein, a handle, a tubular support mounted on said body portion and having a cap adapted to support said handle, binding posts on said cap, wires connected to said binding posts and leading down through said tubular support and connected to said heating element, conductors connected to said binding posts, and a cap adapted to be secured to said support for housing said binding posts and connections and for supporting the adjacent portion of said conductors.

8. In an electric flat iron, the combination of a body portion, a heating element secured therein, a handle, a tubular support mounted on said body portion and having a cap adapted to support said handle, binding posts on said cap, wires connected to said

binding posts and leading down through said tubular support and connected to said heating element, conductors connected to said binding posts, and a cap adapted to be secured to said support for housing said binding posts, and connections, said caps being provided with coacting parts forming a tubular extension adapted to grip the adjacent part of said conductors for supporting them.

9. In a hand operated device of the class described, the combination of a body portion, an electric heating element therein, a handle for said body, a switch carried by said

handle and adapted to be set either open or closed, and electrical connections for the switch and heating element, said handle and switch being constructed and arranged for ready opening and closing of the switch successively as desired by the operating hand during use of said device.

Signed at Detroit this 7th day of September 1912.

CHARLES P. MADSEN.
